UNITED STATES PATENT OFFICE.

LLOYD HOPKINS AND MCKINNEY HOPKINS, OF WYCO, WEST VIRGINIA.

FOLDING DRAFT OR BLOWER PLATE.

Application filed March 28, 1922. Serial No. 547,486.

To all whom it may concern:

Be it known that we, LLOYD HOPKINS and MCKINNEY HOPKINS, citizens of the United States, residing at Wyco, in the county of Wyoming and State of West Virginia, have invented new and useful Improvements in Folding Drafts or Blower Plates, of which the following is a specification.

The invention relates to a folding draft or blower plate.

The object of the present invention is to improve the construction of draft plates or blowers and to provide a simple, practical and efficient draft plate or blower of strong and durable construction adapted to be readily applied to an open fire place or an analogous stove structure and equipped with means for causing it to close tightly against the front frame of the fire place to produce an efficient draft.

A further object of the invention is to provide a folding draft or blower of this character adapted to be readily folded and arranged in an elevated position out of the way and provided with means adapted to counterbalance the folding draft plate or blower and also to cause the same to shift its position and move outwardly at the bottom when folded upwardly, whereby it will securely maintain itself in such folded position.

With these and other objects in view the invention consists in the construction and novel combination and arrangement of parts hereinafter fully described, illustrated in the accompanying drawing and pointed out in the claims hereto appended, it being understood that various changes in the form, proportion and minor details of construction, within the scope of the claims, may be resorted to without departing from the spirit or sacrificing any of the advantages of the invention.

In the drawing, in which like characters of reference designate corresponding parts in the several views:—

Figure 1 is a front elevation of a folding draft plate or blower, constructed in accordance with this invention and shown closed.

Figure 2 is a vertical sectional view of the same.

Figure 3 is a similar view, the draft plate or blower being shown folded in full lines and extended horizontally in dotted lines.

Figure 4 is a detail perspective view of a

combined counterbalancing and shifting bar or member.

Figure 5 is a detail view of one of the clamps.

In the accompanying drawing, in which 60 is illustrated the preferred embodiment of the invention, 1 and 2 designate upper and lower hinged sections of a folding draft plate or blower. The sections, which may be constructed of any suitable material, are 65 adapted to be conveniently made of sheet metal reinforced at the marginal edges, as shown. The upper section, to which the lower section is connected by suitable hinges 3, is suspended and hinged at the top of the 70 front frame 4 of the fender 5 by means of hinge elements, each consisting of a clamp 6. Each clamp 6 consists of an approximately U-shaped body portion forming a recess 7 to receive the lower edge of the 75 top portion 8 of the frame 4 and provided with a front inclined extension 8 and having a clamping screw 9. The U-shaped body portion forms fixed front and rear jaws of the clamp and the clamping screw 9, which 80 is mounted in a threaded opening 10 in the rear jaws, adapted to clamp the top 8 of the frame 4 at the inner face thereof, whereby the clamp is securely fastened in position at the top of the said frame 4. The frame 4 85 is rectangular and the clamps 6 are located at opposite sides thereof and fit against the side portions of the said frame 4. The inclined extensions 8, which project upwardly and outwardly, are provided with inclined 90 bearing slots 11 in which operates an upper pintle rod 12 of the top section or member of the folding plate or blower. The marginal reinforcing rod 13 constitutes the pintle 12 and it is provided at one end of the 95 section 1, near the lower edge thereof, with a laterally extending grip or handle 14 arranged in convenient position to enable the folding plate or blower to be readily swung upwardly or downwardly to open or close 100 the device, as required.

The upper section 1 is equipped adjacent to its upper edge with a combined counterbalancing and shifting bar or member 15 extending across the space between the clamps 105 6 and fitting snugly between the same and secured by bolts 16, or other suitable fastening means, to the upper section 1 of the folding plate or blower. The bar or member 15 is provided at its ends with lugs or flanges 110

2
17 arranged at right angles to the bar or member 15 and having beveled lower portions 18 and provided at their upper portions with recesses 19 arranged contiguous to and fitting the pintle 12. The counterbalancing bar or member projects outwardly and upwardly at the pintle 12 of the upper section and when the folding plate or blower is swung upwardly from its closed position 5 to fold the same at the top of the frame 4, the projecting counterbalancing and shifting bar or member 15 is carried into contact with the top of the frame 4 and thereby causes the hinged portion of the upper section 1 to move outwardly and upwardly along the inclined slots 11 of the extensions 8 of the clamps. The section 1 of the folding plate or blower is inverted when it is swung upwardly in the position illustrated 10 in Figure 3 of the drawing and the outwardly shifting of the hinged portion arranges the folded plate or blower with the center of gravity within the point of support so that the said folded plate or blower will remain 15 in its folded position until it is desired to unfold the same for use. In folding the plate or blower the handle or grip 12 is lifted, causing the lower section to hang in a suspended position and to fall against the normal inner face of the upper section 1. This arrangement brings the lower section exteriorly of the upper section when the plate or blower is folded so that the lower section 20 does not interfere with the action of the counterbalancing and shifting bar or member 15. The weight of the bar or member 15 causes the folding plate or blower to hug tightly the frame 4 when the blower is arranged in its closed position for use, so 25 that the desired draft may be obtained through the bottom of the grate in the usual manner. As the lower section 2 is limited in its swing with relation to the upper section 1 by butt hinges or other suitable means 30 and is prevented from swinging outwardly beyond the plane of the upper section, the counterbalancing and gravity acting bar 15 will operate to hold the lower section, as well as the upper section, in tight engagement with the frame 4. Also this manner 35 of connecting the upper and lower sections of the plate or blower, the said plate or blower may be supported in a projecting horizontal position by a hook 20 of wire or other suitable material, as illustrated in dotted lines in Figure 3 of the drawings, when it is desired to throw the heat downward. Also, the arrangement of the plate or blower in such extended position, when 40 removing the ashes from the grate will, to a large extent, prevent dust from the ashes passing out into the room as such dust will be drawn into the chimney by the draft thereof. The supporting hook 20 may be 45 secured by a screw eye 21 or other suitable

means, to the mantle, board or shelf 22 usually provided over open fire places. Any other supporting means may, of course, be employed for this purpose.

The clamps are provided at their lower 70 portions with projections 23 which are adapted to fill the slots or notches 24 provided in the upper section 1 at the upper edge of the same for the clamps 6. The folding draft plate or blower, which is designed for various kinds of open grates and similar stove structures, is employed in the usual manner for closing the space above the grate to produce a draft through the bottom of the grate when desired, either 75 in starting a fire or when it is desired to cause a fire to burn more quickly and when the fire is burning sufficiently the folding plate or blower is arranged in its folded position at the top of the fire-place. 80 85

What is claimed is:

1. A device of the class described, including spaced clamps having inclined slots and adapted to be secured at the top of an open grate, said clamps being also provided with 90 inclined bearing slots or openings, and a plate or blower having a pintle operating in the said bearing slots or openings and adapted to be swung upwardly over the said clamps, said plate or blower being provided 95 with means for causing it to move outwardly in the said slots or openings when it is swung upwardly.

2. A device of the class described, including spaced approximately U-shaped clamps 100 provided at the back with clamping screws and having extensions at the front, said extensions being provided with inclined bearing slots or openings, and a plate or blower provided with a pintle operating in the bearing 105 slots or openings.

3. A device of the class described, including spaced clamps provided with inclined slots or openings and having depending projections, and a blower or draft plate provided with a pintle to operate in the bearing slots or openings and having slots or recesses at its upper edge to receive the said clamps, said projections being adapted to fill the notches or recesses of the plate or blower. 110

4. A device of the class described, including hinged elements provided with inclined slots or openings, a draft plate or blower having a pintle operating in the slots or openings, and a counterbalancing and shifting bar or member mounted on the draft plate or blower at the hinged edge thereof and arranged to force the hinged edge of the draft plate or blower outwardly in the inclined slots or openings when the draft 115 plate or blower is swung upwardly.

5. A device of the class described, including spaced hinge elements provided with inclined bearing slots or openings, a draft plate or blower having a pintle operating in 120

125

the inclined slots or openings in the said hinge elements, and a counterbalancing and shifting bar or member provided with flanges and fitting between the said hinge 5 elements, said bar or member being adapted to force the hinge edge of the draft plate or blower outwardly when the same is swung upwardly.

6. A device of the class described, including spaced hinge elements having inclined bearing slots or openings, a draft plate or blower provided with a pintle rod operating in the bearing slots or openings, and a counterbalancing and shifting bar or member provided with flanges and fitting between the hinge elements, said flanges being provided at the top with recesses to fit the pintle and having projecting lower portions.

7. A device of the class described, including a draft plate or blower composed of

folding upper and lower sections, the upper section being provided with a pintle, clamps adapted to engage the frame of an open grate at the top thereof and provided with inclined bearing slots or openings receiving 25 the said pintle, and an outwardly off-set counterbalancing and shifting bar secured to the upper section of the folding draft plate or blower between the said clamps and arranged to engage the front of an open fire 30 place to cause the pintle of the draft plate or blower to move outwardly and upwardly in the inclined slots or openings when the draft plate or blower is swung upwardly for folding.

In testimony whereof we have hereunto set our hands.

LLOYD HOPKINS.
McKINNEY HOPKINS.
